[57] **CLAIM**

The ornamental design for a combined golf club head and holographic insert, as shown and described.

DESCRIPTION

FIG. 1 is a bottom perspective view of a combined golf club head and holographic insert showing my new design;

FIG. 2 is a front elevational view thereof;

FIG. 3 is a top plan view thereof;

FIG. 4 is a bottom plan view thereof;

FIG. 5 is an inverted rear elevational view thereof;

FIG. 6 is a left side view of FIG. 1;

FIG. 7 is a right side view of FIG. 1;

FIG. 8 is a top perspective view of FIG. 1;

FIG. 9 is a front elevational view of the holographic insert shown for clarity of illustration;

FIG. 10 is a rear elevational view of FIG. 9;

FIG. 11 is a front edge view of FIG. 9, the undisclosed opposite side being identical; and,

FIG. 12 is a side edge view of FIG. 9, the undisclosed opposite side being identical.
